DESIGN FOR A BOTTLE

Raymond L. Flett, Cincinnati, Ohio, assignor to
The American Products Company, Cincinnati,
Ohio, a corporation of Delaware

Application March 6, 1943, Serial No. 109,683

Term of patent 14 years

To all whom it may concern:

Be it known that I, Raymond L. Flett, a citizen of the United States of America, residing at Cincinnati, in the county of Hamilton, State of Ohio, have invented a new, original, and ornamental Design for a Bottle, of which the following is a specification, reference being had to the accompanying drawing forming a part thereof.

Fig. 1 is a front view of the bottle, showing my new design.

Fig. 2 is a side view of the bottle.

I claim:

The ornamental design for a bottle, as shown.

RAYMOND L. FLETT.
